UNITED STATES PATENT OFFICE

2,048,634

ROLLER GRINDING MACHINE

Joseph R. Keller, Bridgeport, Conn., assignor to
The Black Rock Manufacturing Company,
Bridgeport, Conn., a corporation of Connecti-
cut

Refiled for abandoned application Serial No.
13,042, March 26, 1935. This application De-
cember 5, 1935, Serial No. 53,019

5 Claims. (Cl. 51—49)

This application is a substitute for abandoned application Serial Number 13,042 filed March 26, 1935.

This invention relates generally to grinding machines and has particular reference to machines of this character for grinding and thereby truing rollers so that they will have a true cylindrical surface.

The machine has been especially designed for grinding comparatively small cylindrical rubber and composite rollers employed for various purposes including platens such as are used in typewriters.

The object of the invention is to provide a simple form of machine of this character employing but a single grinding wheel which is directly driven and adapted for various adjustments with respect to the roller to be ground so that a true cylindrical surface will be produced by the grinding operation and whereby the work may be performed on both new and old rollers very accurately and quickly.

The machine is of an elongated design provided with means for rotatably supporting the roller to be ground longitudinally of the frame, while the grinding element is mounted above the roller and fed longitudinally thereof so that the cuttings from the roller are thrown clear of the operating mechanisms of the machine. A screw feed serves to move the electrically driven grinding wheel backward and forward through change gear and clutch mechanisms enclosed within the speed box. By reason of the fact that the grinding wheel is hung from above the roller and operates against the side of the roller to be ground and its means of adjustment with respect to the roller, the machine is capable of operating upon rollers varying in size between relatively wide limits and with which truly cylindrical rollers may be formed.

Other features and more specific objects of my invention will become readily apparent to persons skilled in the art from a consideration of the following description, when taken in conjunction with the accompanying drawings wherein

Fig. 1 shows a rear perspective view of my improved small rubber roller grinding machine, partly broken away;

Fig. 2 shows a front elevation, on an enlarged scale and partially broken away, of the same machine;

Fig. 3 shows a vertical cross section through the machine, taken on line 3—3 of Fig. 2;

Fig. 4 shows a vertical longitudinal section through the drive mechanism contained within the head-stock of the machine, and taken on line 4—4 of Fig. 5;

Fig. 5 shows a vertical cross section through the same drive mechanism taken on line 5—5 of Fig. 4;

Fig. 6 shows an enlarged vertical longitudinal section of the tail-stock and its mounting shown in Figs. 1 and 2;

Fig. 7 shows an enlarged vertical cross section taken on line 7—7 of Fig. 2, and showing hand operating means for the clutch;

Figs. 8 and 9 show a side view and an end view respectively of a modified form of tail-stock adapted for holding a rubber roller having extended metal spindle portions adapted to run in bearings;

Figs. 10 and 11 show a longitudinal section and end view respectively of a coupling for drive spindle;

Fig. 12 shows an enlarged longitudinal section taken on line 12—12 of Fig. 5; and

Fig. 13 shows a similarly enlarged elevation of the rear side of the speed box, and cooperating with that shown in Fig. 12 for operating a clutch in the speed box.

As before stated this machine was originally designed for grinding rubber and rubber composition rollers which are more or less yieldable due to the softness of material, consequently provision has been made for acquiring delicate adjustments, and relative speeds for the roller and cutting element so as to insure accurate grinding, yet it should be understood that the machine is equally well adapted for grinding rollers of other compositions and materials as for instance, leather surfaced rollers, wood rollers and the like, with little or no change in the machine other than possibly to substitute different cutting wheels, which may be readily accomplished.

Referring in detail to the characters of reference marked upon the drawings, 15 represents a supporting leg for one end of the machine which carries a guide shaft support 16; 17—17 represent spaced-apart legs for the other end of the machine and upon which a gear box 18 is supported and between which a motor 19 is hung. The said end supports are tied together by lower spacing bars 20—20 and upper carriage guide rods 21 which together with the said end supports form a rigid frame structure of the machine. It will thus be apparent that it would be a comparatively simple matter to construct machines of this

type and by the use of longer or shorter bars produce a longer or shorter machine for grinding longer or shorter rollers, as might be required.

The motor 19 adjustably mounted on the legs 17 5 includes a drive shaft 22 for carrying a vari-speed pulley 23 shown upon the end of the machine in Fig. 1, and which is connected by a belt 24 to a driven pulley 25 on a comparatively short shaft 26, one end of which is journaled in bearings of 10 the housing and the other end in a web 27 extending from the front to the rear wall of the housing 18. This shaft 26 carries a small pinion 28, see Figs. 4 and 5, that meshes with two larger gears 29 and 30, one mounted upon the work revolving spindle 31 and the other mounted upon a 15 third shaft 32 of the change speed mechanism. This spindle and shaft 32 are journaled in the opposite side portions of the housing and extends freely through the before mentioned web 27. 20 Upon the inner end of the shaft 31 is mounted a center and work driver 33 which serve to support and drive one end of the roller A to be ground.

The shaft 32 serves to drive the change speed 25 gear mechanism which is mounted in part upon said shaft 32 and upon shafts 34 and 35 and feed screw shaft 36, all of which will be next described. A cluster of three gears 37 of different diameters 30 are slidably mounted upon the shaft 32 and are adapted for engagement with large gears 38, 39 and 40 on the before mentioned shaft 34 whereby said shaft 34 may be driven at three different speeds with respect to the shaft 32.

A two-gear cluster 41 is slidably mounted upon 35 the intermediate shaft 34 that is adapted to mesh with the gears 42 and 43 upon the short shaft 35 which is journaled in part in a bracket 44 secured to the sides of the gear housing. The cluster gears 41 which are splined to the shaft 34, are 40 adapted to be moved longitudinally thereon through a shifting lever 45, its rocker shaft 46 and a depending arm 47. The cluster 37 is likewise 45 slidable upon its shaft 32 for engagement with either of the three large gears through a shifting lever 48, its rocker shaft 49 and depending arm 50. Both these levers 45 and 48 are mounted on their respective shafts outside of the gear housing, as is clearly shown in Figs. 2 and 5.

On this short shaft 35 is mounted a small gear 50 51 which drives an idler gear 52 that in turn meshes with and drives a small clutch-faced gear 53 that is loosely mounted upon the screw shaft 36. A second gear 54 is mounted on the inner end of the shaft 35 and meshes with a second 55 clutch-faced gear 55 loosely mounted on the screw shaft 36 and is held against longitudinal movement by a collar 56.

A slide clutch sleeve 57 is splined to the screw shaft 36 intermediate of the two clutch-faced gears 53 and 55 for driving the screw either 60 forward or backward. This clutch sleeve 57 may be either hand or automatically operated through a slide rod 58, see Fig. 1, one end portion of which is slidably mounted in opposite walls of the gear housing and extends longitudinally of the machine and has its other end similarly mounted in the upper portion of the guide shaft support 16.

The automatic means for operating the slide rod and clutch comprises a sleeve 59, see Figs. 4, 5 and 70 12, which is provided with an annular flange 60 upon each end and an integral projected arm 61 having a forked end portion 62 that engages the annular groove in the clutch sleeve 57, and whereby the same is operated. The shifting rod 58 75 passes freely through a lug 63 secured to the

motor carriage 64, see Fig. 3, and serves as a means for engaging either of the adjustable collars 65 mounted upon the rod 58, which, when engaged by the said lug, serve to automatically operate the rod, and through additional means shown in Figs. 12 and 13 to shift the clutch and reverse the direction of rotation of the screw and movement of the carriage.

This additional mechanism referred to, and associated with the rod and clutch, is to insure the quick disengagement of the clutch sleeve from either clutch-face gears, and the prompt engagement of the opposite face of the clutch sleeve with the opposite clutch-face gear; thereby preventing the slide clutch member from remaining in a neutral position. In this connection, attention is again directed to Figs. 4, 5 and 12, wherein it will be seen that adjacent to the before-mentioned clutch mechanism a sleeve 59 is mounted upon the rod 58 intermediate of collars 66—66 secured to the rod, and that coil springs 67 are so mounted upon the rod intermediate of said collars 66 and the ends of the sleeve 59 as to be compressed with the preliminary movement of the rod, causing engagement of the collar 65, see Fig. 3 with the lug 25 63 until the high side of the collar 66 engages the free end of one of the latches 68 and raises its tooth out of engagement with the flange 60 on the end of the sleeve 59. This release of the latch permits the sleeve to be thrown forward so that the flange on the other end of the sleeve will ride under and into engagement with the tooth of the second latch, which obviously serves to shift the clutch 57 and cause the carriage to be moved in an opposite direction. In this connection, it will be 35 seen that by simply changing the position of the adjustable collars 65 on the trip rod 58, the carriage can be made to travel longer or shorter distances, as may be necessary, according to the length of the rollers to be ground. By this means, the grinding wheel can be operated backward and forward the length of the roller to be ground, as often as may be necessary, to insure a perfect cylindrically finished roller.

In this connection, and as before suggested, it 45 is also possible for the operator to manually reverse the movement of the carriage at any time by means of a hand lever 69, see Figs. 2 and 7, which is hinged to a bracket 70 adjustably mounted on the rear guide bar 21 while another portion of the lever is operatively connected to a stud 71 50 adjustably secured to the carriage reversing trip rod 58, after which the said rod can readily be slid backward or forward to perform the tripping operations. It will also be understood that when 55 the bracket 70 is reset on the rear guide bar 21, it will be necessary to reset the bracket bearing the stud 71 with which the operating lever is also connected.

It is also possible to stop the movement of the 60 carriage by an operation of the lever 69 and its rod 58, if one or the other of the latches 68 are previously raised, which raising movement is accomplished, see Figs. 1, 12 and 13, by an adjustment of one of the two limit pins 72 that are 65 mounted in brackets 73 upon the outside of the gear housing 14, and provided with a slot to accommodate a small pin 74 carried by the limit pin 72. The upper end of this limit pin serves for the engagement of an arm 75 mounted upon 70 the end of the short shaft 76 upon which the latch 68 is mounted.

In order to insure the latches normally lying in their lower position, a spring 77 is provided, one end being secured to the gear housing and 75

the other to the free end of the arm 75. There are obviously two of these limit pins 72 and associate mechanisms, one for each of the latches 68, as will be readily understood from Figs. 12 and 13. In this respect it will be apparent that when the limit pin is down, as shown to the left in Fig. 13, the latches are free to act normally, whereas if raised to the position shown on the right in Fig. 13 the latch would be brought out of operated position and thus insure the stopping of the carriage at one end of its travel. It will be obvious from the foregoing that by the raising of both of the limit pins, a stoppage of the carriage in any position can be accomplished by the hand lever 69, when travelling in either direction, by a manual sliding movement of the rod 58 to bring its clutch 57 to an intermediate position.

The cutting element may be in the form of an abrasive wheel or other suitable cutter, designated as 78, and is mounted directly upon the motor shaft and hung to operate at a right angle to the roller A and can be driven to turn with or against the roller.

The motor is enclosed in a frame 79, the top portion of which is secured to a member 80 which is dove-tailed to receive corresponding dove-tailed ways 81 of the motor carriage 64. This motor carriage is provided with two sets of aligned bushings 83, two of which receive the front guide rods 21 and the other aligned pair the rear guide rod 21 so that the carriage will be free to move longitudinally on the rods, with the motor and its grinding wheel suspended therebeneath. Referring to Fig. 3, it will be seen that the member 80 is provided with a threaded nut 84 that is engaged by an adjusting screw 85 journaled in the motor carriage and whereby the motor and its grinding wheel may be adjusted forward and backward with respect to the face of the roller.

The before-mentioned feed screw 36, see Figs. 2 and 3, passes through an internally threaded sleeve 86 to one end portion of which a small pinion 87 is secured while a collar 88 is also secured to the other end of the sleeve in a way to hold it in the bearing of the upright 89 against endwise movement. The sleeve of course is held from rotating within its bearing so that with the turning of the screw, as by power, the carriage will be fed lengthwise of the machine in one direction or the other according to the direction the shaft is rotated; whereas on the other hand, if the machine is not running and it is desired to adjust the carriage, it can be accomplished through the gear 90 mounted upon the shaft 91 journaled in the upper part of the said upright 89, and provided with an adjusting wheel 92. In this connection, it will be observed that when the machine is mechanically driven, the gear 90 and shaft 91 are held against rotation by means of set screw 93 which in turn holds the smaller gear 87 and its sleeve 86 against rotation forming so to speak a fixed nut within the bearing for the engagement of the feed screw 36.

The tail stock 94 shown in Figs. 1, 2 and 6 is of a design employed for grinding rollers on centers; whereas when grinding rollers having journals *a*, as indicated in Figs. 8 and 9, a pair of journal supports 95 similar to that shown in Figs. 8 and 9 would be employed, one for each end journal *a* of the roller, though the roller would be driven from and in line with the driving shaft 26, in which case a flexible drive chuck 96, such as shown in Figs. 10 and 11, would be employed. The lower portion 97 of the tail stock 94 shown in Fig. 6 and the journal support 95 shown in

Figs. 8 and 9 are similar, whereas the upper portions of these two designs of supports are adapted to receive the ends of the two types of rollers.

Referring therefore to said Figs. 6, 8 and 9, it will be seen that the lower or base member 97 is mounted upon the front bar 20 having a flat undersurface 98 adapted to be engaged by clamping means comprising a shaft 99, an eccentric 100 and an operating lever 101 which serves to align and secure the base 97 in any position upon the 10 rod. While the upright 102 of the tail stock and the upright 103 of the journal bearing are different in detail, yet they are both adapted to be adjustably mounted on the base member 97. The said base member is provided with ways 104 to receive a corresponding rib in the tail stock 94 and support 95 so as to permit crosswise adjustment of the roller with respect to the base 20, and an adjusting screw 105 that engages a tapped lug 106 serves to move the pedestal forward and backward.

The upright journal support 95 is provided with an elongated concaved recess to receive a correspondingly shaped bushing 107 in which the end of the roller bearing *a* is mounted. This bearing is held in position and rotates under the outer end of an arm 108 that is secured to a vertical shaft 109 loosely mounted in the bearings of the support 110. This shaft 109 also passes through a locking member 111 which is provided with a threaded shank to receive a nut 112 which, when operated, serves to draw the locking member up against the side of the shaft to clamp it in position.

The upright 94 serves to enclose mechanism 35 comprising the upper portion of the tail stock and includes a center 113, a quill 114 which receives the center, and in part encloses a spring 115, one end of which is seated within the quill and the other against an adjusting screw 116 mounted in the end portion of the upright. The center may be drawn back against the action of the spring for the placing of a roller in the machine through a small lever 117 that is suitably fulcrumed and engages a pin 118 secured in the 45 quill, as is clearly shown in Fig. 6.

In Figs. 10 and 11, I have shown a flexible drive chuck to be mounted on the end of the work spindle 31 for driving the grinding rollers having journal ends *a*, as shown in Fig. 8, instead of 50 pindle ends. This chuck comprises a sleeve 119 that is adapted for attachment on the end of the work spindle 31 by means of a set screw as shown, and includes an internal annular pocket 120 to receive the flanged end of a holder 121 55 to support one of the end journals *a*, when secured therein by a set screw 122. Spaced-apart pins 123 carried by the sleeve 119 serve to engage slots in the flanged end of the holder 121 so as to provide a flexible driving connection for 60 the holder and its journal *a* by the shaft 31 and its sleeve.

Having thus described my invention, what I claim and desire to secure by Letters Patent is:

1. In a roller grinding machine, the combination with a frame of a feed screw journaled in the frame supports, a driving spindle, a tail stock adjustably mounted upon the frame and in alignment with the axes of the said driving spindle, a driving shaft, connections therewith for driving 70 the spindle, change speed gearing through which the feed screw is operated, a clutch mechanism intermediate the change speed mechanism and the feed screw whereby the latter may be driven forward or backward, a carriage slidably mounted 75

above the driving spindle and tail stock and connected to be moved longitudinally by the feed screw, a motor and grinding wheel adjustably mounted upon the underside of the carriage in 5 a manner to operate on a roller carried below on the spindle and tail stock, an automatic trip mechanism adapted to be engaged and operated by the motor carriage to operate the clutch in a way to reverse the rotation of the feed screw.

10 2. In a roller grinding machine, the combination with a frame comprising a pair of lower bars, a pair of guide rods positioned above the said bars, a feed screw between the said guide rods, a driving spindle, a tail stock mounted upon 15 the said lower bars and in alignment with the axes of the said driving spindle for supporting a roller to be ground, a driving shaft, connections therewith for driving the spindle, change speed gearing through which the feed screw is operated, 20 clutch mechanism intermediate the change speed mechanism and the feed screw whereby the latter may be driven forward or backward, a carriage slidably mounted upon the guide rod and connected to be moved longitudinally by the feed screw, a motor and grinding wheel adjustably mounted upon the underside of the carriage and beneath the guide rods in position to operate 25 upon a roller when carried by the spindle and tail stock, an automatic trip mechanism adapted to be engaged and operated by the motor carriage and to operate the clutch in a way to reverse the rotation of the feed screw, and hand operating means for shifting the clutch to reverse the direction of rotation of the feed screw.

30 3. In a roller grinding machine, the combination with a frame comprising end supports of a pair of lower bars connecting the supports, a pair of guide rods also connecting said supports and positioned above the said bars, of a feed screw positioned between the said guide rods and journaled in the said supports, a driving spindle, a tail stock adjustably mounted upon one of the said lower bars and in alignment with the axes of the said driving spindle, a driving shaft, connections therewith for driving the spindle, change 35 speed gearing through which the feed screw is operated, a clutch mechanism intermediate the change speed mechanism and the feed screw whereby the latter may be driven forward or 40 backward, a carriage slidably mounted upon the guide rod and connected to be moved longitudinally by the feed screw, a motor and grinding wheel adjustably mounted upon the carriage and beneath the guide rods in

position to operate upon a roller when carried below by the spindle and tail stock, an automatic trip mechanism adapted to be engaged and operated by the motor carriage and to operate the clutch in a manner to reverse the rotation of the feed screw. 5

4. In a roller grinding machine, the combination with spaced apart upper and lower frame members of a feed screw associated with the upper frame members, a driving spindle and tail stock positioned intermediate of the upper and lower frame members adapted to support a roller to be ground, a clutch mechanism through which the feed screw is operated, a carriage slidably mounted upon the upper frame members and connected with and adapted to be fed longitudinally of the feed screw, a motor and grinding wheel mounted upon the carriage in position to operate upon the roller when carried by the spindle and tail stock, an automatic trip mechanism adapted to be engaged and operated by the motor carriage, comprising a slide rod connected with the clutch and carrying a lug to be engaged by the carriage, a cushioning means mounted upon the slide rod, including a sleeve upon 15 the rod through which the clutch is manipulated, springs upon the rod in engagement with the ends of the sleeve and collars upon the rod against which the opposite ends of the springs abut, and pawls to engage and disengage the collars 20 and sleeve whereby the two alternately engage and release the latter.

5. In a roller grinding machine, the combination with spaced apart upper and lower frame members of a feed screw associated with the upper frame members, a driving spindle and tail stock positioned intermediate of the upper and lower frame members adapted to support a roller to be ground, a clutch mechanism through which the feed screw is operated, a carriage slidably mounted upon the upper frame members, a sleeve journaled in the carriage and threadably mounted on the feed screw, a pinion secured to the sleeve, a gear meshing with the pinion, a shaft for the gear, hand means for operating the shaft, gear sleeve and carriage independent of the feed screw, means for locking the shaft and sleeve against rotation to insure longitudinal movement of the carriage with respect to the feed screw, a motor and grinding wheel mounted upon the carriage in position to operate upon the roller when carried by the spindle and tail stock. 40 45 50

JOSEPH R. KELLER.
